UNITED STATES PATENT OFFICE.

UGO ROSSI, OF MILAN, ITALY.

APPARATUS FOR CONCENTRATING LIQUIDS.

1,152,977.

Specification of Letters Patent.

Patented Sept. 7, 1915.

Application filed June 3, 1911. Serial No. 631,057.

To all whom it may concern:

Be it known that I, Dr. Ugo Rossi, a subject of the King of Italy, residing at 11 Via Panizza, Milan, in the Kingdom of Italy, have invented certain new and useful Improvements in Apparatus for Concentrating Liquids, of which the following is a specification.

The present invention has for its object 10 a tubular evaporation apparatus for concentrating liquids which is able to operate freely at atmospheric pressure or at a reduced pressure on fitting to it a suitable suction pump or a barometric condenser or both 15 simultaneously in lowering the temperature to 50 or 55 degrees.

A constructional form of the apparatus is illustrated by way of example in the accompanying drawings, in which:—

20 Figure 1 shows an element in section. Fig. 2 shows the same in plan. Fig. 3 is a side elevation. Fig. 4 shows the method of raising the liquid in an elementary tube. Fig. 5 shows a helical device arranged at 25 the bottom of each elementary tube. Fig. 6 is a general view. Fig. 7 is a plan corresponding to Fig. 6.

The apparatus consists broadly of a nest 30 of tubes D bent at the lower part in such a manner that their orifices are located on one and the same horizontal plane in a chamber B inclosed in a steam chamber L and headed at both ends into two plates P P'; the curvature of the tubes enables them to expand 35 freely.

The liquid that it is desired to evaporate enters the chamber B; S is a divider of the cyclone type intended for completely separating the vapor from the jets of liquid and 40 the foam carried along with it.

The liquid to be concentrated enters the chamber B from which it ascends to the desired height and to the same level in the tubes; the heating vapor coming from a generator provided for this purpose enters 45 through the orifice V and escapes condensed at T (Figs. 1 and 2); as a result of this heating the liquid contained in the lower part of the tubes boils and when the bubbles 50 of vapor are numerous and voluminous the vapor acquires a high velocity by means of which it forces in front of it and carries along with it the liquid which it spreads in a small uniform layer over the entire surface of the tube. In proportion as it ascends the evaporation increases because the

temperature of the heating vapor is greater as is also the velocity of the vapor which issues violently from the upper apertures of the tubes and is mixed with small drops of 60 the condensed liquid.

It is necessary to separate the pulverized liquid from the vapor and this is effected in the divider S; the vapor enters the latter tangentially and assumes a very rapid 65 rotatory movement around the central cone c, the drops and the foam becoming united under the influence of centrifugal force against the walls of the inclosing cylinder and the steam while continuing to rotate 70 as indicated by the arrow issues through the central diaphragm at G in the same manner as in the cyclones which serve to separate dust from atmospheric air.

In order to guarantee the uniformity of 75 the layer and of the travel of the liquid to be evaporated in the inner wall of the nest of tubes a helical guide is fixed at their lower orifice (Fig. 5) and serves to impart a 80 rotatory movement to the liquid which then ascends in large spirals (Fig. 4) along the inner walls of the tubes.

Several evaporating elements can be connected one with the other in such a manner 85 that the vapor issuing from the first serves as heating vapor for the second the vapor from the second for heating the third until the latter condenses its vapor *in vacuo*.

In Fig. 6 where α is the barometric condenser, β the tube supplying the condensation water γ the vacuum and δ the steam supply tube three elements I, II, III are 90 shown combined to form a triple-acting evaporation system.

In the drawing it will be noticed that the 95 concentrated liquid of the first element passes through the tube A to the second element and the concentrated liquid of the second element passes through the tube A' to the third element so that a continuous circulation is obtained to the outlet from which the liquid issues concentrated to the desired 100 degree. In this manner a continuous concentration is obtained in a single passage through the apparatus.

As shown in Fig. 6 the exhaust vapor can 105 be utilized at T for heating the liquid which is to undergo the desired concentration this being effected by means of heating chambers R communicating one with the other by means of tubes Z and with the first nest of tubes by means of the first length of tube T.

The present invention is intended to comprise every modification relating to the construction and the arrangements that could be adopted without departing from the general idea set forth in the present specification and the accompanying drawing.

What I claim and desire to secure by Letters Patent of the United States is:—

1. A tubular evaporation apparatus for 10 concentrating liquids comprising in combination a chamber containing the liquid to be evaporated, a plurality of inclined tubes curved at their lower ends only the said curved lower ends of the tubes opening in 15 the same horizontal plane into said liquid chamber so as to permit of a uniform feed of the liquid and also the expansion of the tubes, a casing containing the said tubes, means for conducting steam through the 20 said casing to heat the liquid contained within the said chamber and the lower ends of said tubes, means in communication with the upper ends of the said tubes for separating the pulverized liquid from the steam as 25 the same escapes from the tubes, means for leading off the dry steam from the said separating means and means for collecting the concentrated liquid.
2. A tubular evaporation apparatus for 30 concentrating liquids comprising in combination a chamber containing the liquid to be evaporated, a plurality of inclined tubes curved at their lower ends only, the said curved lower ends of the tubes opening in 35 the same horizontal plane into the said liquid chamber so as to permit of a uniform feed of the liquid and also the expansion of the tubes, a short curved helical baffle

plate disposed with the lower curved ends of each of the tubes, for imparting a rotary movement to the liquid as it ascends within the tubes, a casing containing the said tubes, means for conducting steam through the said casing to heat the liquid contained within the said chamber and the lower ends of said tubes, means for separating the pulverized liquid from the steam as the same escapes from the tubes, means for leading off the dry steam from the said separating means, and means for collecting 50 and leading away the concentrated liquid.

3. In an evaporator system, each evaporator comprising a cylindrical casing containing inclined nests of tubes headed into upper and lower plates, the lower ends of said tubes being bent so as to open at the same level into a chamber for containing the liquid to be evaporated, means for circulating heating vapor through said casing and around said tubes, a separator arranged at 60 the upper end of said tubes and in communication therewith, a hollow cone arranged within said separator, means for conducting steam from the interior of said hollow cone to the cylindrical casing of a second evaporator in series with the first, and means connected to the base of said separator for conducting liquid and foam particles to the liquid chamber at the base of the cylindrical casing of the said second evaporator.

In testimony whereof I affix my signature in presence of two witnesses.

UGO ROSSI.
